UNITED STATES PATENT OFFICE.

MALCOLM M. MACDONALD, OF TACOMA, WASHINGTON.

BUILT-IN PIANO.

Application filed May 2, 1923. Serial No. 638,176.

To all whom it may concern:

Be it known that I, MALCOLM M. MACDONALD, a citizen of the United States, residing at Tacoma, in the county of Pierce and State of Washington, have invented certain new and useful Improvements in Built-In Pianos, of which the following is a specification.

This invention relates to a built-in piano, designed primarily for dwellings, but it is to be understood that a built-in piano in accordance with this invention can be set up in connection with any structure wherein it is found applicable, and the invention 15 has for its object to provide in a manner as hereinafter set forth, a built-in piano whereby the inclosing casing therefor is built of the same material and finished similar to the woodwork of the room in which the 20 piano is installed, thereby dispensing with the employment of costly piano cases, and furthermore so set up the built-in piano whereby the wall of the room is utilized as a part of the piano, under such conditions 25 providing for material saving in floor space, at the same time improving the tone of the piano through the elimination of all surplus vibration in making the piano wall-tight.

30 Further objects of the invention are to provide a built-in piano for dwellings which is simple in its construction and arrangement, strong, durable, compact, ornamental to the room in which it is installed, having 35 its body substantially the same as the ordinary piano, capable of being installed at materially less expense than the cost of the ordinary piano, overcoming the cost of the moving of pianos from point to point, readily installed, thoroughly efficient in its use, and comparatively inexpensive to set up.

With the foregoing and other objects in view, the invention consists of the novel construction, combination and arrangement 45 of parts as hereinafter more specifically described, and illustrated in the accompanying drawings, wherein is shown an embodiment of the invention, but it is to be understood that changes, variations and modifications 50 can be resorted to which fall within the scope of the claims hereunto appended.

In the drawings wherein like reference characters denote corresponding parts throughout the several views:

55 Figure 1 is a perspective view of a built-

in piano in accordance with this invention.

Fig. 2 is a vertical sectional view thereof.

Fig. 3 is a section on line 3—3 of Fig. 2.

Fig. 4 is a sectional plan of a modified form.

As is well known, the practice of economy enters greatly into the planning and construction of a modern home, and that built-in features are becoming more and more 65 indispensable; and it would seem that the things, which in the greatest degree add to the charm and comfort of the home should come in for a share of this consideration, and no one will dispute the fact that a 70 piano is materially essential for a modern home, for no other instrument contributes more to the delight of home-loving people, and it is obvious, in view of the foregoing, that a built-in piano becomes a thing of 75 great value, as it has many advantages over the ordinary upright piano, particularly relative to the economy of space for the reason that a built-in piano forms a part of the wall and requires much less floor 80 space than the ordinary upright piano, and furthermore a built-in piano eliminates the costly case work of the ordinary piano, as the casing of the built-in piano will consist of the same material and finished similar 85 to the woodwork of the room in which the piano is installed and further the body of the piano is constructed practically the same as the ordinary instrument and is of high 90 grade, both in material and construction. It is also obvious that when setting up a 95 built-in piano, the piano is made wall-tight, under such conditions that the tone of the piano is greatly improved by the elimination of all surplus vibration and a piano is provided where its richness and high quality are an indisputable fact. Then furthermore, the installation of a built-in piano can be had at materially less expense than the cost 100 of the ordinary piano, and the costly moving of pianos is also obviated.

Referring to the drawings, wherein is shown a built-in piano, in accordance with this invention, 1 denotes the wall of the room provided with a pocket 2 and arranged 105 forwardly of the pocket 2, as well as forming a continuation thereof, is a casing 3.

The pocket 2, as well as the casing 3, have arranged therein the piano actions and sounding board.

The casing 3 is built of the same material and finished similar to the woodwork of the room in which the piano is installed.

The pocket 2 may be dispensed with, and the rear of the casing 3 formed by the wall 1 of the room, and the piano actions as well as the sounding board can be arranged in the built-in casing 3 entirely.

The casing 3 can be set up with a plurality of compartments 4, and closed by hinged doors 5. The key board of the piano is indicated at 6.

The casing 3 can be so set up relative to the wall 1, that one end of the casing 3 will form a continuation of one end of the wall, and the said end of the casing 3 will be finished in the same manner as the woodwork at the end of the wall 1.

In Fig. 3 of the drawings, the casing 3 has one end thereof arranged at one end of the wall 1, whereas in Fig. 4 the casing 3 has its ends arranged intermediate the ends of the wall 1.

The front and top of the casing 3, are constructed in the same manner as an ordinary piano case, with the exception that below the key board 6 the compartments 4 and doors 5 are arranged. The casing 3 has a central clearance so that access can be had to the pedals 8. Panels 9 and 10 are provided for closing the back of the compartments 4 and the central clearance. The rear of the casing 3 is closed by the wall 1. The key board is closed by a hinged cover 11, and the top 12 is also preferably hinged. The music rack is indicated at 13. The shape of the casing 3 corresponds to the shape of the casing of an upright piano.

Although the preferred embodiment of a built-in piano in accordance with this invention is as described and illustrated, yet it is to be understood that changes in the details of construction can be had which will fall within the light of the invention as claimed.

What I claim is:

1. A built-in piano comprising the combination with the wall of a room, of a piano action enclosing casing secured to and having its back formed by said wall, said casing formed of the same material and finished similar to the woodwork of the room in which the casing is installed.

2. A built-in piano comprising the combination with the wall of a room, of a piano

action enclosing casing open at its rear, said casing built against, secured with and having its rear closed by said wall.

3. A built-in piano comprising the combination with the wall of a room, of a piano action enclosing casing open at its rear, said casing built against, secured with and having its rear closed by said wall, and said casing further consisting of material corresponding to and finished similar to the woodwork of the room in which the casing is installed.

4. A built-in piano comprising the combination with the wall of a room, of a piano action enclosing casing open at its rear, said casing built against, secured with and having its rear closed by said wall, and said casing further consisting of material corresponding to and finished similar to the woodwork of the room in which the casing is installed, and said casing further including a plurality of compartments and hinge doors for closing said compartments, said doors arranged in front of the casing.

5. A built-in piano comprising the combination with the wall of a room, of a piano action enclosing casing provided with a key board and open at its rear, said casing built against, secured with and having its rear closed by said wall.

6. A built-in piano comprising the combination with the wall of a room, of a piano action enclosing casing provided with a key board and open at its rear, said casing built against, secured with and having its rear closed by said wall, and said casing constructed of material similar to the woodwork of the room in which the casing is installed and finished similar to said woodwork.

7. A built-in piano comprising the combination with the wall of a room, of a piano action enclosing casing provided with a key board and open at its rear, said casing built against, secured with and having its rear closed by said wall, and said casing constructed of material similar to the woodwork of the room in which the casing is installed and finished similar to said woodwork, and said casing further provided with compartments arranged below said key board.

In testimony whereof, I affix my signature hereto.

MALCOLM M. MACDONALD.
